UNITED STATES PATENT OFFICE.

SIDNEY SMITH, OF CAMBRIDGE, MASSACHUSETTS.

DIGESTER.

SPECIFICATION forming part of Letters Patent No. 443,924, dated December 30, 1890.

Application filed June 29, 1889. Serial No. 316,060. (No model.)

To all whom it may concern:

Be it known that I, SIDNEY SMITH, of Cambridge, in the county of Middlesex and State of Massachusetts, have invented certain new 5 and useful Improvements in Digesters, of which the following is a specification.

This invention relates to a digester having an inner coating composed of sulphite of lime or other chemical salt precipitated and 10 fixed uniformly on all parts of its inner surface that are exposed to the liquid contents, said coating being produced by the direct impingement or action of the heated products of combustion of any suitable fuel upon the 15 outer surface of the metal of the digester and the contact at the same time of a suitable solution with the inner surface of the digester, the result being the deposition of a chemical salt or incrustation, which protects the metal 20 from injury during the subsequent operation of cooking wood chips in an acid liquor.

The object of the invention is to produce 25 a pulp digester which may be maintained at a uniform temperature and may be readily controllable, whereby the digester is lined or coated with a chemical incrustation, the constituents of said interior coating being derived from the liquor used in digesting the pulp or being such constituents as are employed in such digesting fluid.

The invention consists, further, of an arrangement of dampers and flues surrounding the digester, so arranged that the temperature and pressure within the digester can be 35 raised, perfectly controlled, and maintained. The arrangement of flues and dampers also makes possible a rapid cooling down of the surrounding flues, which is desirable previous to the expulsion of the contents of the digester, by blowing off under any desired pressure. Openings covered by mica are cut 40 through the surrounding brick-work into the flues at suitable points for observing the action of the hot gases and for the insertion of any convenient device for determining the 45 temperature in the flues. The fire-box stands in connection with the chimney by means of a direct flue, and also by means of the series of indirect flues surrounding the digester, so 50 that by use of dampers the products of combustion may be taken directly to the chimney without touching the digester, or may be al-

lowed to stream up and around the digester, passing finally to the chimney. As shown in the drawings, the walls of the final or "down" 55 flue are so curved as to deflect the hot gases and air and compel them to travel close to the digester-shell. At the front of the fire-box openings covered by doors are placed in the brick-work, so that cold air may be drawn 60 in on a level with and directly over the highly-heated fuel. This air is not intended for increasing the combustion, but is rather intended to check the increase, but at the same time to better utilize the heat already 65 produced by carrying it forward to the flues around the digester and diffusing it in a uniform manner. The fire is thus prevented from becoming too intense, and the accelerated circulation prevents injurious 70 concentration of the heat upon the nearest portions of the digester-shell and tends to the production of a nearly uniform temperature throughout the flues. An opening is provided for the admission of cold air to the flues 75 extending along the digester, so that by opening a door covering said opening the walls of the casing surrounding the digester may be rapidly cooled down to prevent injury to the digester by the radiation of heat from said walls 80 upon the digester after the contents of the latter have been blown off or otherwise removed.

In the accompanying drawings, forming a part of this specification, Figure 1 represents 85 a side elevation of a digester and a vertical section of the casing inclosing the same and of the fire-box and flues. Fig. 2 represents a section on line *x x*, Fig. 1. Fig. 3 represents a section on line *y y*, Fig. 1. Fig. 4 represents a section on line *z z*, Fig. 1.

The same letters and figures of reference indicate the same parts in all of the figures.

In the drawings, *a* represents the digester, which is constructed of boiler-iron or steel 95 or other suitable material, and is inclosed in the casing or setting *b* of masonry, said casing being separated from the digester by a space which surrounds the digester, excepting at the top, where the top of the casing is 100 brought into the walls of the digester. Said space is partially divided by two vertical partitions *c c*, which extend vertically from the base or foundation portion of the casing

- nearly, but not entirely, to the top of the casing, and convert the space surrounding the digester into two flues *e f*, the former being called the "upward" and the latter the "downward" flue. Each partition *c* is composed of a vertical brick wall *g*, extending inwardly from the inner wall of the casing or setting partly, but not entirely, across the space between said wall and the digester, and a flexible sheet *10*, of asbestos board, set edgewise in said wall and extending across the remaining portion of said space, its outer edges being free to bend or move and bearing yieldingly against the periphery of the digester.
- 15 This construction permits the digester to expand and contract freely without injuring the setting by its expansion and without forming streaks between its periphery and the partitions *c* by its contraction.
- 20 *g* represents the furnace or fire-box, which is located at the lower end of the upward flue *e*, but not directly under the same, as shown in Fig. 1, and communicates with the flue *e* through an opening *h* over the bridge-wall *i'*.
- 25 One side of said opening is curved, as shown at *h'*, said curve connecting the arched top of the fire-box with the vertical outer side of the flue *e* and forming not only an enlargement of the opening *h*, but also a surface which
- 30 guides the heated products of combustion so that they do not impinge directly on the bottom of the digester, as would be the case if the top of the fire-box joined the outer wall of the flue *e* at a right angle, said products
- 35 of combustion being caused to assume a vertical direction by the curved surface *h'* rather than by impingement against the surface of the digester. Overheating of the digester at the portion nearest the opening *h* is thus prevented.
- 40 In the walls of the fire-box are openings for the admission of cold air, arranged as near the level of the fire as possible, so that cold air may be admitted to the top of the fire
- 45 and be there mingled with the heated products of combustion. The air thus admitted does not promote combustion, but carries the heat forward through the flues *e f*, diffuses it uniformly, and prevents an excess of heat.
- 50 Said openings may be made especially for this purpose, as shown at *i*, Fig. 1; or the fire-door may have a lower section *j*, which is connected to the main portion of the door by horizontal hinges, so that it can be opened by
- 55 swinging it upwardly, thus forming an opening for the admission of air close to the level of the fire.
- k* represents a series of passages arranged to conduct air through the heated bridge-wall
- 60 and deliver the same to the fire-box.
- m* represents a slide or damper, which is arranged to close the opening *h* when it is desired to shut off the heat from the flues *e f*. When said slide or damper is closed, the heat
- 65 passes through the flue *n* at the bottom of

the casing to the direct flue or stack *o* without contact with the digester.

p represents an opening in the casing for the admission of cold air to the lower portion of the flue *e*, so that when it is desired to rapidly cool the walls surrounding the digester a door *q* in said opening may be opened and cold air admitted to the flues *e f*. The object of thus cooling the walls is to prevent injury to the digester by radiation of heat from said walls when the contents of the digester have been blown out. It is necessary to quickly discharge the contents of the digester when the cooking has reached a certain stage, and if the walls are not quickly cooled serious injury to the digester will result from the radiation of heat from the walls. The opening *p* affords suitable means for the rapidly cooling of the walls. The lower portion of the flue *f* communicates with the direct flue or stack *o* by a passage *f'*, through which the products of combustion pass to the stack. The wall of this downflue is curved to deflect the hot gases and air against the lower curved end of the digester-shell.

In the upper portion of the direct flue *o* is a slide or damper *r*, which, when opened, is moved outwardly or away from the wall *s*, that separates the flue *o* from the flue *f*. The object of said damper is mainly to contract the flue *o* and cause the heat to impinge against the wall *s* in its upward passage, the damper closing toward said wall, so that the products of combustion in escaping have to pass between the damper and wall. The escaping heat is therefore partially utilized by heating the wall *s*, and thus maintaining a higher temperature in the flue *f*.

w represents a sight-opening formed in the casing *b* to permit the inspection of the flues, so that the conditions therein existing may be readily determined. Said opening is covered with a sheet *u*, of mica or other suitable transparent material. There may be any desired number of these openings, and they may be located at any desired points.

2 represents a blow-off pipe, which extends from the lower portion of the digester to permit the discharge of the contents thereof.

3 represents a vertical pipe within the digester for the circulation of the liquor therein. Said pipe has two arms *4 4*, attached to and extending horizontally from its upper end and bearing at their outer ends on a shoulder *5* on the digesters. The object of said arms is to support the pipe *3* and keep it at the center of the digester, and this is accomplished by the bearing of said arms on the shoulder *5*. The arms are preferably made of lead to resist the action of the chemicals.

The formation of the coating is not confined to any one liquor, nor is it necessary that the liquor used for the purpose of producing the coating should at the same time be adapted for "cooking" the wood or fibrous material,

for the digester may be first lined by means of appropriate liquor, and then used with any other liquor suitable to act upon the wood without at the same time injuring the coating previously formed.

The digester may be made of any metal or material capable of withstanding the temperature and pressure employed in the process.

10 An essential feature of the invention is the direct impingement or action upon the outside of the material forming the digester of the heated products of combustion of any suitable fuel, whereby the presence on the inner 15 side of said material of any solution capable of yielding a deposition forms a coating for the interior of the digester in the application of heat, said deposition being fixed at the same time and by heat. While it may be the 20 most convenient and practicable way to fill the digester when in position for use with a suitable liquor and then apply heat externally to produce an inner coating, the underlying principle involved is not that of fusion 25 of certain ingredients and baking upon the shell, as in the case of an enamel, but is the chemical deposition of the salt or substance forming the coating by decomposition or concentration, accomplished by heat in the manner described.

A good process of providing the interior of the digester-shell with a protecting-coating is as follows: The digester, which is set in a casing of brick-work and heated by the products of combustion passing through the 35 ascending and descending flues, is first filled with wood chips about to the point where the conical lead-lined neck is attached to the digester. Acid liquor, which is designed to act 40 upon the gums, resins, &c., of the wood, is now admitted to the digester. While the liquor is running in the digester is gently heated by allowing the heat from a low fire to pass through the flues. An observer looking down 45 into the digester from the top will note that the white coating has already begun to form where the liquor has come in contact with the already-heated shell of the digester. No definite temperature need be adhered to. It 50 is only necessary to keep the temperature low enough not to injure the digester-shell or send forth sulphurous-acid gas in amounts large enough to seriously inconvenience the workmen engaged in filling the digester. 55 When the liquor has reached the junction of the lead lining with the steel shell, the cover is securely bolted on and the fire is urged. If the formation of the coating were the only object at stake, the digester might be strongly 60 fired from this point on; but as a uniform and complete cooking of the wood is an important element in the process it is the practice to slowly bring the pressure and temperature within the digester up to the maximum 65 desired only after the lapse of some four or five hours. These maximum conditions of temperature and pressure are then maintained

as carefully as possible until the operator is assured that the wood chips are completely freed from the incrusting gums, &c.

The total time of cooking from the time the man-hole plate is bolted on to the time when the cooked pulp is blown out from the pipe at the bottom is a variable one, but may be from fifteen to twenty hours. When the 75 contents have been blown out at the end of the cooking process, that part of the interior which has been in contact with the liquor will be found coated with a thin, firm, uniform incrustation. If bisulphite of magnesium were 80 the liquor used, the incrustation will consist of a white coating of monosulphite of calcium or of monosulphite of magnesium. Both the steel of the shell and the lead lining of the neck will be coated to the height covered 85 by the liquor during the whole time of cooking. There is no coating where the liquor has not been in contact with a metallic surface, and for this very reason the neck and inner side of the man-hole cover are lined 90 with lead to protect the iron beneath from the action of the sulphurous-acid gas which is expelled from the liquor by heat and collects above the level of the liquor in the expansion-chamber formed by the neck. The 95 monosulphite of calcium adheres wherever it comes in contact with a metallic surface which is heated from the opposite side. Some of the monosulphite of calcium is deposited upon the pulp and must be subsequently 100 washed out before the pulp is made into paper.

Heretofore sulphite-digesters have generally been heated by free steam or a steam-coil on the inside or by a steam-jacket on the 105 outside, while in this case the source of heat is the combustion of any suitable fuel outside the shell of the digester and in direct communication with the said shell, so that the products of combustion act directly thereon. 110 Therein lies the marked difference in method and the cause for a marked difference in results, for the incrustation can be perfectly formed only when the shell is heated by the direct impingement or action of the heated 115 products of combustion of a suitable fuel on the digester with the proper liquor in contact with the plate.

The process herein described of forming a protecting inner coating for the digester as 120 well as the coating itself does not form part of the subject-matter of the claims in this case, since the above are embraced by my pending application for patent, filed March 7, 1889, Serial No. 302,277.

I claim—

1. The herein-described improved apparatus for producing pulp, comprising the digester, the furnace or fire-box, a casing enclosing the digester, upward and downward 130 flues surrounding said digester, and a stack or chimney outside of said casing, said upward flue extending upwardly from and communicating with the rear portion of said fire-

box, and the lower end of said downward flue connecting or communicating directly with said stack or chimney, substantially as and for the purposes set forth.

5 2. The combination, with a digester, of a furnace or fire-box, a casing inclosing the digester and subdivided to form upward and downward flues extending along the digester, said upward flue extending upwardly from 10 and communicating with the rear portion of the fire-box, and openings through the walls of the fire-box above the fire therein for the admixture of cold air with the heated products of combustion immediately above the 15 fire, as set forth.

3. In an apparatus for producing wood pulp from chips of wood under the action of bisulphite liquor or other chemical salt and forming a continuous inner protecting-coating 20 on the digester, the combination of the digester, a casing therefor having upward and downward flues throughout the length of said digester, and a fire-box or furnace located at and to one side of the bottom of said upward 25 flue and opening thereinto and provided with cold-air-supply openings, and having its arch or top curved or deflected upwardly to join the vertical wall of said flue at said opening, whereby the products of combustion are prevented from impinging directly on the bottom 30 of the digester and a nearly uniform temperature is secured, substantially as set forth.

4. The combination of a digester, a casing 35 therefor having upward and downward flues, a fire-box or furnace located at the bottom of the upward flue, a direct flue or stack located beside the downward flue and communicating with the lower end thereof, and a damper in 40 said direct flue, whereby the heated products of combustion may be caused to impinge against the wall which separates the downward flue from the direct flue, as set forth.

5. The combination of a digester, a casing 45 therefor having upward and downward flues, a fire-box or furnace communicating with the lower portion of said upward flue, and an opening for the admission of cold air into the lower portion of the upward flue, as set forth.

50 6. The combination of the digester having

an internal shoulder 5 at its upper portion, and the circulating-pipe 3, having the arms 4 bearing on said shoulder, whereby the pipe is removably supported above the lower end of the digester, as set forth.

7. The combination, substantially as hereinbefore set forth, of a sulphite-digester, a furnace or fire-box offset or removed from the digester, a conduit communicating with the fire-box and with the exterior of the digester 60 and adapted to conduct the products of combustion to and along or in contact with the exterior of the digester, means for controlling or shutting off the communication between said fire-box and conduit, whereby the action 65 of the products of combustion on the digester may be controlled, and a stack or chimney communicating with said furnace or fire-box, as set forth.

8. The combination, substantially as hereinbefore set forth, of a sulphite-digester, a furnace or fire-box offset or removed from the digester, a stack or chimney, a conduit communicating with both the fire-box and chimney and arranged to conduct the products of 70 combustion along or in contact with the exterior of the digester, means for controlling or shutting off the communication between said fire-box and conduit to control the action of the products of combustion on the digester, 75 and another conduit or flue adapted to conduct the products of combustion from the fire-box directly to the chimney, avoiding the digester, as set forth.

9. The combination of a digester, a casing 80 of masonry having vertical partition-walls which subdivide the space between the digester and the casing into flues, and flexible sheets of asbestos incorporated into said walls and extending edgewise therefrom to the periphery of the digester, the inner edges of 85 said sheets being free to bend and bearing with a yielding pressure on the digester, as set forth.

In testimony whereof I affix my signature in 90 presence of two witnesses.

SIDNEY SMITH.
